PUPPET

Saundra B. Seron, 1170 Say Road, Santa Paula, Calif.

Filed Dec. 19, 1958, Ser. No. 53,836

Term of patent 14 years

(Cl. D34—2)

FIG. 1.

The broken line showings are for illustrated purposes only.

I claim:

The ornamental design for a puppet, as shown and described.
